UNITED STATES PATENT OFFICE.

JOHN W. DORAN, OF WILKES-BARRÉ, PENNSYLVANIA, ASSIGNOR TO THE WILKES-BARRÉ MANUFACTURING COMPANY, OF SAME PLACE.

DESIGN FOR A CURTAIN.

SPECIFICATION forming part of Design No. 27,522, dated August 17, 1897.

Application filed June 24, 1897. Serial No. 642,199. Term of patent 14 years.

To all whom it may concern:

Be it known that I, JOHN W. DORAN, a citizen of the United States, residing in Wilkes-Barré, county of Luzerne, State of Pennsylvania, have invented and produced a new and original Design for Curtains, of which the following is a specification.

The leading feature of my design is a curtain having the configuration and representation illustrated in the accompanying drawings, in which—

Figure 1 represents a curtain exhibiting my design, and Fig. 2 is an enlarged detail view of a portion of the edge thereof.

In the drawings, A is a curtain having a scalloped edge B, having the individual scallops *b* and the undulating-line effects *d* adjacent thereto, so as to present the effect of an indented purl edge.

What I claim is—

The design for a curtain, substantially as shown.

JOHN W. DORAN.
